[57] **CLAIM**

The ornamental design for a radio base mounting unit or
similar article, substantially as shown and described.

DESCRIPTION

FIG. 1 is a front, top and right side perspective view of
a radio base mounting unit or similar article showing my
new design with the broken line radio shown for illustra-
tive purposes only and forming no part of the
claimed design;

FIG. 2 is a left-side elevational view thereof;

FIG. 3 is a rear elevational view thereof; and

FIG. 4 is a bottom plan view thereof.

FIG. 1
